Patented Aug. 24, 1976

241,122

CONTAINER FOR TWO SHAVING UNITS

Derrick Raymond Gatley, Maidenhead, England, assignor to Wilkinson Sword Limited

Filed Dec. 3, 1973, Ser. No. 420,955

Claims priority, application Great Britain June 22, 1973

Term of patent 14 years

Int. Cl. D9—03

U.S. Cl. D9—186

FIG. 1.

FIG. 4.

FIG. 5.

FIG. 2.

FIG. 3.

FIG. 1 is a perspective view from above of the front and one side of a container for two shaving units showing my new design;

FIG. 2 is a rear elevational view thereof;

FIG. 3 is a bottom plan view thereof;

FIG. 4 is a sectional view thereof taken on line 4—4 in FIG. 2; and

FIG. 5 is an elevational view thereof of the side not visible in FIG. 1.

I claim:

The ornamental design for a container for two shaving units, as shown and described.
